United States Patent Office.

GEORGE W. HERRICK, OF STUYVESANT, NEW YORK.*

Letters Patent No. 96,110, dated October 26, 1869.

BASE-BURNING STOVE.

The Schedule referred to in these Letters Patent and making part of the same.

To all whom it may concern:

Be it known that I, GEORGE W. HERRICK, of Stuyvesant, in the county of Columbia, and State of New York, have invented a new and improved Coal-Stove; and I do hereby declare that the following is a full, clear, and exact description thereof, which will enable others skilled in the art to make and use the same, reference being had to the accompanying drawings, forming part of this specification.

Figure 1 represents a vertical central section of my improved coal-stove.

Figure 2 is a horizontal section of the same, taken on the plane of the line x x , fig. 1.

Similar letters of reference indicate corresponding parts.

The object of this invention is to construct a heater for burning western bituminous coal, and other tar-coal depositing much lamp-black; and

The invention consists, chiefly, in providing for ample draught, so that all the products of combustion, and the solid matter carried off with the same, will be burned.

For this purpose, I have provided both an upward and downward direct draught to, and lateral escape for the products of combustion from the fire-place, as hereinafter more fully described.

A, in the drawing, represents the body or outer shell of an upright coal-stove, of cylindrical or other suitable form.

B is the grate, and

C, the base of the stove.

Within the shell A is arranged, above the fire-place, a vertical cylinder, D, which has a feed-opening, E, extending from its upper end to and through the side of the shell A, as shown.

Certain of the heated products of combustion es-

cape, through the apertures a of the cylinder D, into the annular chamber formed between itself and the outer case A; and arise in said chamber to escape into the flue F.

This causes air to be drawn into the cylinder D through the pipe E, and also through the base C and grate B, a door, d, being formed in said base for such purpose.

The door d and pipe E are provided with dampers or valves, of ordinary or any suitable construction, thus providing for regulating the main supply of air.

Apertures c are arranged through the sides of the shell, opposite, or nearly so, to the apertures a , as shown.

Through these apertures c , air is drawn in to mix with the still burning gases that arise from the fire-place, to aid in their combustion.

These springs c also serve to make the apparatus an illuminating-stove, without the use of mica-front and other devices formerly employed for that purpose.

In the drawing, the course of the products of combustion is shown by red, that of the air by blue arrows.

Having thus described my invention,

I claim as new, and desire to secure by Letters Patent—

The shell A, provided with the apertures c , in combination with the draught-cylinder D, which has the apertures a , all arranged substantially as described, to facilitate the combustion of the gases, and to constitute an illuminating-stove, as set forth.

GEORGE W. HERRICK.
